UNITED STATES PATENT OFFICE.

JOHN SEDLIN, OF CHICAGO, ILLINOIS.

MEANS FOR SEVERING SHEET METAL.

1,252,727.

Specification of Letters Patent.

Patented Jan. 8, 1918.

Application filed June 19, 1916. Serial No. 104,376.

To all whom it may concern:

Be it known that I, JOHN SEDLIN, a citizen of the United States, and resident of Chicago, in the county of Cook and State of Illinois, have invented certain new and useful Improvements in Means for Severing Sheet Metal, of which the following is a full, clear, and exact specification.

This invention relates to improvements in means for severing sheet metal and other hard, stiff materials on straight and curved lines, heretofore requiring separate pairs of opposing cutting edges or blades, one for severing on straight lines, another for severing on curved lines, and for the latter as many pairs of cutting edges as there are differences in the curves to be cut.

The prime object of my invention broadly stated, is to provide a single pair of opposing cutting edges with means adapting them for severing sheets of metal and other materials on both curved and straight lines, and the one to the exclusion of the other.

A further object of my invention is to provide for such an arrangement of the severing edges of such an implement that the curved cutting edge is adapted to coöperate with the other and opposing edges for severing a sheet of material in a straight line, and that all of said edges are adapted to sever with a shear like action without bending the metal, or producing bur or other rough edges.

Another object of my invention is to provide the opposing cutting edges with means for severing sheet metal on curved lines beginning with a cut on the arc of a circle.

A further object of my invention is to provide a simple and effective stop device for limiting the opening and closing movement of the opposing cutting edges, for adjusting the opposing cutting edges to sheets of differing thickness, and for preventing their frictional wear from passing each other.

Another object of my invention is to provide another and master stop for and adapted to limit the severing action of the cutting edges to the curved cutting portion thereof, and which at the same time is adapted to substantially and materially facilitate the control and quicken the severing of the sheet material on a curved line and lines.

With these ends in view, my invention finds embodiment in certain features of novelty in the construction, combination and

arrangement of parts by which the said objects and certain other objects are attained, all as hereinafter fully described with reference to the accompanying drawings, and more particularly pointed out in the claims.

In said drawings:

Figure 1 illustrates in side elevation a cutting implement provided with cutting edges in which my invention finds its embodiment.

Fig. 2 is a front end elevation thereof.

Fig. 3 is a detail perspective view of the straight and curved cutting edges therefor.

Fig. 4 is a front elevation of a modified form of the curved cutting edges.

Fig. 5 is a sectional detail thereof on the line 5—5 of Fig. 4, and—

Fig. 6 is a plan view of a piece of sheet steel illustrating a few of the many different forms of cuts producible from the operation of the implement of my invention.

Similar characters of reference indicate the same parts in the several figures of the drawing.

In Figs. 1, 2 and 3 of the drawings 7 and 8 indicate jaws, of which the jaw 7 is provided with an outwardly inclined bevel 9 producing a cutting edge 10 extending in a straight line transversely the full width thereof, the jaw 8 being provided with an inwardly inclined bevel 11, producing a straight edge 12, extending at an oblique angle to the cutting edge 10, merging at one end into an outwardly curved edge 13, terminating in a point 14, bisecting a bevel 15 of the adjacent edge of the jaw 8 and opposing the straight edge 10.

It will now be observed that when the cutting edges are moved to a closed position, the cutting edge 10 overlaps the cutting edge 12 and in parallel planes, with the result that the curved cutting edge 13 coöperates with the straight cutting edge 12 to sever a sheet in a straight line, the length of which is that of the combined length of the curved and straight edge of the jaw 8, and that on the other hand when the closing movement of the jaws is limited to the inner end of the curved edge 8 the cut of the opposing edges is limited and restricted to the severing of a sheet on a curved line.

As a means for manually operating an instrument provided with the severing edges of my invention, the jaws 8 are pivoted together by means of a set screw 16 and respectively provided with handles 17 and 18

between which is preferably seated a coiled spring 19 for normally maintaining the jaws in an open position.

Spring 19 is preferably sleeved upon a 5 pin 20 projecting laterally from the handle 17, and preferably screw-threaded therein, as indicated at 21, one end of which spring may be, if desired, seated in a recess 23 in the handle 18, the primary object of which 10 recess, however, is to provide a seat coöperating with the pin 20 to furnish a closing stop preventing the cutting edges passing beyond each other to become dulled from frictional or striking contact with the opposing surfaces of the jaws when severing on a straight line.

For limiting the expansion of the spring and thereby adjusting the opening between the cutting edges, a screw-threaded bolt 24 20 is passed through the handle 18 to adjustable contact with the end of the pin 20, the bolt being preferably passed loosely through the handle and screw-threaded into the pin as indicated at 25, so that the head 26 of the 25 bolt by its engagement with the handle will operate as a stop limiting the open movement of the cutting edges accordingly as the screw-threaded bolt 24 is moved inwardly or outwardly from the pin 20.

30 This adjustment of the outward movement of the opposing cutting edges is an important feature of my invention in that it provides a means for accurately adjusting the normal opening between the cutting edges 35 to the opposing surfaces of the sheets of material differing in thickness, whereby lost motion in closing the jaws for making the initial cut is reduced to a minimum, and the control of the cutting edges for directing 40 them along both straight and curved lines is accordingly facilitated for the reason that from the instant that the point 14 penetrates the sheet, the cutting edges have such a grip on the material that they may be 45 directed along predetermined lines on moving the sheets or the cutting edges accordingly, and with the greatest ease, and accuracy for following the predetermined lines upon which the sheet is to be severed.

50 Moreover, it may be observed that with the cutting edges adjusted just close enough to prevent the sheet from passing the point 14 the slit opening produced by the operation of the straight cutting edges will 55 operate with the point in directing the straight cutting edges along the line preceding their successive severing actions.

When, however, it is desirable to successfully sever a sheet along predetermined 60 straight lines merging into curved lines, and vice versa, and particularly when the lines are on arcs of circles of comparatively large diameter, the opening between the jaws is so adjusted to the sheet of material that while 65 fitting closely, it may be passed more or less

freely between the point 14 and the portion of the straight edge opposed thereto, and especially when of such a diameter that a portion of the straight edge may be utilized when severing along such a line, and in 70 which case the severing operation on curved lines may be accordingly quickened.

My invention further includes the employment of another and "master stop" so designated for the reason that it not only operates 75 to restrict the severing action of the opposing cutting edges to the projection and point formed by the curved edge, and prevents the accidental operation of the straight edges, but provides a means by which the 80 point may be successfully utilized to sever the sheet with a shear-like action.

This master stop may be of any form or arrangement adapted for securing the above results, but as shown in the drawing, consists of a tongue 27 pivoted at one end to the handle 18 by means of a screw 28, the length of which tongue is such that at the instant the point 14 has passed through the sheet to be severed the further movement of the 90 opposing cutting edges is prevented by the contact of the handle 17 with the end of the tongue, whereby the length of the closing and opening movement of the opposing cutting edges when adjusted to the thickness 95 of the sheet is limited to that thickness.

In other words the stroke of the cutting edges is then so short that it is possible and practical for the operator to locate the perforations made through the sheet by the 100 point so close together that the severed edges will appear to have been made with a shear-like action as will be better understood by bearing in mind that in addition to its severing action the point 14 operates as a pivot 105 from which to swing the opposing cutting edges for directing them along both curved and straight lines.

As a means for supporting the tongue in its operative position the surface upon which 110 it is pivoted is provided with a recess forming a shoulder 31.

The master stop is preferably used only when severing sheets of material on curves of comparatively small diameter, and when 115 along a very short straight line merging into a curve, but for severing on arcs of circles of comparatively large diameter and long straight lines, the master stop is swung away from its supporting shoulder 31 formed by a 120 recess in the handle 18 and from the path of movement of the handle 17.

My invention, however, is not limited to the precise form and arrangement of the opposing straight and curved cutting edges 125 hereinbefore shown and described, as will be seen by reference to Figs. 4 and 5 wherein the end of the edge 10 of the jaw 7 opposing the curved edge 13 is curved inwardly in a plane with the edge 10 as indicated at 32, and 130

the straight edge 12 of the jaw 8 is also curved inwardly as indicated at 33, the curvatures in both instances being extended along the side edges of the jaws, and the 5 jaws being so arranged that the convex surface of the outer edge of the jaw 8 projects into the concavity of the inner surface of the jaw 7, or in other words, the inner surface of the jaw 7 overlaps the side edge of 10 the jaw 8.

When the jaws are thus formed, a means is provided whereby the entering cut for a curved line may be produced upon the arc of a circle, and which may possibly be desirable in some instances for starting from a straight line or edge a cut on a curved line, and as may be with very little practice. 15

It is here to be observed, however, that there is no form of curved cut that cannot, 20 as before described, be made with the implement shown in Figs. 1, 2 and 3, and that with the construction of a cutting implement corresponding exactly or substantially with that illustrated in Fig. 1 of the drawings, it is both possible and practical to sever 25 sheet materials, and particularly sheet metal, along any of the continuous lines illustrated in Fig. 6, and which, it is proper to add, furnishes an illustration of but a 30 very few of the many differing forms of cuts producible with such an implement.

A cutting implement in which my invention finds its embodiment is not only adapted 35 and useful for producing in sheet materials of various kinds patterns of numerous design, and the construction of cornices and other sheet metal work requiring the use of irregular or ornamental joints, but is particularly adapted and useful for severing 40 templets for die and tool work from sheet metal requiring as they do the accurate severing of sheet metal along predetermined irregular lines indicated thereon and frequently requiring to be drawn to scale, and 45 heretofore necessitating the use of punches and a chisel or straight edge shears so difficult of being used with accuracy as to frequently require the cutting of several sheets for the production of a single templet, and 50 in any event at an objectionable expense in time, labor and cost.

In this connection it seems proper to observe that in practice it is found with the use of the opposing cutting edges of my invention an ordinary mechanic can produce 55 a perfectly constructed templet from sheet metal, either of steel or iron, and in one quarter the time, and with corresponding less labor and effort than from the use of 60 any implement or implements heretofore known or used for that purpose.

With the employment of handles 17 and 18 for manually operating the severing edges, a pin 34 secured to and projecting inwardly from the handle 17 in register with

a perforation 35 in the handle 18 forms a simple and convenient means for the perforations of the sheets and particularly templets for stringing together or hanging them on a nail. 70

In conclusion it should also be understood that my invention is not limited to a hand manipulation of the jaws nor to the use of pivoted jaws for operating the opposing severing edges as hereinbefore described for 75 following and severing either curved or straight lines, and that therefore my invention includes any means for so actuating the jaws as to enable the cutting edges thereof to operate as hereinbefore described. 80

Having described my invention, what I claim and desire to secure by Letters Patent is:—

1. A portable severing mechanism comprising a pair of cutting members, both of 85 which are provided with opposing straight cutting edges, one of said straight cutting edges being provided with a severing point projecting outwardly therefrom and adapted to coöperate with the edge of the opposing member to cut materials on a curved line, a portion of said cutting member adjacent to said point arranged to coöperate with the opposing cutting member to cut material on a straight line, and means for 90 operating said members. 95

2. A portable severing mechanism comprising a pair of cutting members, both of which are provided with opposing straight cutting edges inclined relatively to each 100 other, one of said straight cutting edges being provided with a severing point, projecting outwardly therefrom, and adapted to coöperate with the edges of the opposing member to cut material on a curved line, the 105 portion of said cutting member adjacent to said point arranged to coöperate with the opposing cutting member to cut material on a straight line, and means for operating said members. 110

3. A severing means comprising a pair of opposing straight cutting edges, the end of one of which gradually merges to a cutting point projecting in the path of movement of the cutting edge opposed thereto, and 115 means adapted for manually operating and bodily directing said edges along alternately curved and straight lines.

4. A severing means comprising a pair of opposing straight cutting edges, the end of 120 one of which terminates in a cutting point projecting in the path of the cutting edge opposed thereto, means for limiting the closing movement of said edges, and means adapted for manually operating and directing the cutting action of said edges. 125

5. A severing means comprising a pair of opposing straight cutting edges, the end of one of which gradually merges to a cutting point projecting in the path of movement of 130

the cutting edge opposed thereto, means for adjustably limiting the closing movement of said edges, and means for manually operating and directing the cutting action of 5 said edges.

6. A severing means comprising a pair of opposing cutting edges, the end of one of 10 which edges terminates in a cutting point projecting in the path of movement of the cutting edge opposed thereto, means for limiting the opening movement of said edges, and means for manually directing the cutting action of said edges.

7. A severing means comprising a pair of 15 opposing straight cutting edges, the end of one of which merges to a cutting point, projecting in the path of movement of the cutting edge opposed thereto, means for adjustably limiting the opening movement of said edges, and manual means for directing the cutting action of said edges.

8. A severing means comprising a pair of 20 opposing cutting edges, the end of one of

which edges terminates in a cutting point projecting in the path of movement of the cutting edge opposed thereto, an adjustable stop for limiting the opening movement of the opposing cutting edges, and means for manually directing the cutting action of 25 said edges.

30 9. A severing means comprising a pair of opposing straight cutting edges, the end of one of which diverges to a cutting point projecting in the path of movement of the cutting edge opposed thereto, a swinging stop adapted to limit the closing movement of said edges when and for severing on curved lines, and means for manually directing the cutting action thereof.

35 In witness whereof, I have hereunto set my hand and affixed my seal, this 13th day of May, A. D. 1916.

JOHN SEDLIN. [L. S.]
